US0D1025998S

(12) **United States Design Patent** (10) **Patent No.:** **US D1,025,998 S**
(45) **Date of Patent:** **** May 7, 2024**

(54) **SUPPORT FOR ELECTRONIC DEVICES**

(71) Applicant: **Jiajia He**, Liuzhou (CN)

(72) Inventors: **Jiajia He**, Liuzhou (CN); **Chenglan Huang**, Liuzhou (CN)

(73) Assignee: **Jiajia He**, Liuzhou (CN)

(**) Term: **15 Years**

(21) Appl. No.: **29/844,228**

(22) Filed: **Jun. 28, 2022**

(30) **Foreign Application Priority Data**

Jan. 18, 2022 (CN) 202230034078.0

(57) **CLAIM**

The ornamental design for a support for electronic devices, as shown and described.

DESCRIPTION

FIG. 1 is a perspective view of a support for electronic devices showing our new design;

FIG. 2 is another a perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof in an unfolded configuration.
